Primary Examiner — Nathan M Johnston(74) *Attorney, Agent, or Firm* — ePatentManager; Guerry Grune(57) **CLAIM**

The ornamental design for a spooled item holding device, as shown and described.

DESCRIPTION

FIG. 1 is a top perspective view of the spooled item holding device showing my new design;

FIG. 2 is a front elevation view thereof;

FIG. 3 is a back elevation view thereof;

FIG. 4 is a right end elevational view thereof;

FIG. 5 is a left end elevational view thereof;

FIG. 6 is a front elevation view of an embodiment of the slip-resistant spooled item holding device of FIG. 1; and, FIG. 7 is an exploded top perspective view of the spooled item holding device of FIG. 1.

The sides not explicitly shown in the drawings are a mirror image of the sides visible in the drawings.
